WATCH CRYSTAL GRINDING APPARATUS

Grady L. Sharp and William A. Sharp,
Albuquerque, N. Mex.

Application October 30, 1950, Serial No. 192,925

5 Claims. (Cl. 51—101)

1

The present invention relates to machines for automatically grinding watch crystals or other types of crystals to any desired shape or size, and, if desired, with bevelled edges at any desired angle of bevel. The machine is arranged to operate entirely automatically so that once a blank crystal has been set on the machine and it has been set in operation, the machine will thereafter automatically operate to grind the crystal to the desired shape and size to fit a particular bezel. The machine operates entirely automatically without attention from the operator, and, if desired, it may be automatically stopped by a timer after a predetermined period of time. One of the objects of the invention is to provide a machine fully automatic as in the foregoing, which will grind a crystal to a desired shape and size without the attention of the operator.

Another object of the invention is to provide an automatic crystal grinding machine having means wherein a crystal-holding mechanism is provided and which is operated by a mechanism arranged to rotate the crystal and to cause it to move in a manner so as to exactly follow the shape of a watch bezel which is rotated by other means.

Another object of the invention is to provide a crystal grinding mechanism having means for rotating a watch bezel and having follower means associated with the bezel and cooperating means whereby a crystal to be ground can be caused to follow the exact shape of the watch bezel whereby to grind the crystal in a manner to exactly fit the watch bezel.

Another object of the invention is to provide an arrangement as in the foregoing object, wherein the rotation of the crystal and the bezel are exactly synchronized to produce a ground crystal to fit the bezel exactly.

Another object of the invention is to provide an arrangement as in the foregoing objects including automatic means for moving the crystal mounting or carrier means transversely so as not to cause a groove to be worn in the grinding wheel.

Another object of the invention is to provide an automatic crystal grinding mechanism, including a mounting frame for the crystal, the frame having a tilt adjustment whereby a bevel can be ground on a watch crystal at any desired angle.

Another object of the invention is to provide a crystal grinding mechanism, comprising a means whereby a watch bezel may be rotated, a follower associated with the bezel, means whereby the

2

crystal is caused to move in exact conformity with said follower, the arrangement involving a frame for mounting the crystal, and an adjustment whereby its position may be adjusted toward and away from the grinding wheel to accommodate the mechanism to crystals or blanks of greater size than the size to which the crystal is to be ground.

Another object of the invention is to provide in a crystal grinding machine a mounting frame and holder for crystals comprising two spindles having means to synchronize their speed and embodying resilient pads for clamping the crystal, the arrangement comprising a manually reciprocatable stem and spring tensioned jaws which may be moved into a position by the stem to clamp the crystal.

Another object of the invention is to provide an improved chuck for use in a crystal grinding machine wherein two pairs of diametrically opposed jaws are provided, each pair of jaws being operated by a screw threaded stem having left and right hand threads whereby the two pairs of jaws may be caused to engage the inside of a watch bezel whereby to firmly hold the bezel whereby it may be rotated and it may have a follower caused to accurately follow the inside contour of the bezel as it is rotated.

Further objects and numerous advantages of our invention will become apparent from the following detailed specifications and annexed drawings wherein Fig. 1 is a general perspective view of the watch crystal grinding mechanism of our invention.

Fig. 2 is an enlarged detailed view of the frame, mounting and holding mechanism for the crystal to be ground.

Fig. 3 is a detailed view of the universal joint drive for the arbors which rotate the crystal.

Fig. 4 is a detailed view of a modified form of flexible coupling to the crystal drive.

Fig. 5 is a detailed view of the improved rotatable chuck mechanism for mounting and rotating the watch bezel.

Fig. 6 is another view of the mechanism of Fig. 5.

Fig. 7 is a detail view of a part of Fig. 1.

Referring now more in detail to Fig. 1 of the drawings the entire mechanism may be mounted on a rectangular base 10. Numeral 12 designates an electric motor of suitable size and speed for driving the mechanism.

On the shaft of the motor 12 is a grinding wheel 14 of conventional type which is attached to the motor shaft by a nut as shown. On the

end of the shaft of motor 12 is a pinion gear 16 which meshes with a large gear 18 on a shaft 28. The shaft 28 is mounted in upright pedestals from the base 10, having bearings 24 and 26 as shown. On the end of the shaft 28 is a bevel gear 30 which meshes with another bevel gear 32 on a right-angled shaft 34 which is mounted in a pedestal bearing 36. Also on the shaft 34 is another bevel gear 38 which meshes with the bevel gear 40 on a right-angle shaft 93 which will be referred to again presently. The shaft 34 also carries and drives the improved rotatable chuck of our invention which will be referred to again presently.

The gear ratios of gears 16 and 18 may preferably be such that the shaft 28 rotates at a speed of 6 revolutions per minute. The gear ratios of the gears 30 and 32 may preferably be such that the shaft 34 rotates at a speed of 3 revolutions per minute, so that the chuck 42 rotates at 3 revolutions per minute. As will presently be described the crystal itself is rotated at exactly the same synchronized speed as the chuck 42, that is, a speed of 3 revolutions per minute. The manner of drive of the crystals will be described presently.

The chuck 42 has 2 pairs of diametrically opposed jaws as can be seen in Fig. 1. These jaws protrude from the interior of the chuck 42 and each pair is individually adjustable by knurled knobs 44 and 46. The details of the improved chuck 42 will be described presently in connection with Figs. 5 and 6. The 2 pairs of jaws of the chuck 42 engage internally within a bezel 48 which is shown as rectangular in Fig. 1 and the outer surface of these jaws are knurled or roughened so as to engage the interior of the bezel without slipping. Numeral 52 designates a curved, pointed member which engages within the interior of the bezel 48 in the groove in the bezel in the manner of a cam follower and exactly follows the interior contour of bezel 48 as it rotates. The member 52 is a part of a mechanism which it operates to cause the movement of the crystal to be ground to exactly follow the movement of the bezel 48 and this mechanism will be described presently.

Referring now to the rotatable drive for the crystal mounting, the manner of this drive will be described. The details of the rotary drive for the crystal mounting are shown more clearly in Fig. 3. Referring now to Fig. 3 of the drawings numeral 128 designates a pedestal bearing in which is mounted shaft 93 of bevel gear 40. Bevel gear 40 through its shaft drives the shaft 96 through the universal joint 94 which serves the conventional purpose of universal joints. The shaft 96 is square for part of its length, as shown, and it engages in a square bore or opening in a shaft 98 to provide slidable adjustment as between these two shafts, that is, the arrangement provides an extensible coupling. At the other end of the shaft portion 98 is another universal joint 92 which connects this shaft to a shaft mounted in a transverse member 130 which attaches to the frame of the crystal mounting as will be described presently. On the end of this shaft is another bevel gear 90 which meshes with a right-angle gear 88 on the end of the shaft 114, which, as may be seen in Fig. 1 forms one of the spindles which drive the crystal as will be described. From the foregoing it can be seen that the bevel gear 88 drives one spindle of the crystal rotating mechanism. It will also be observed that the entire gear train comprising gears 90, 88 and the gear 82 on the same shaft as gear 88 may be

moved transversely along with the crystal mounting frame, as will be described shortly. Movement of this gear train both transversely and toward and away from the grinding wheel 14 is permitted by the universal joints and the sliding coupling formed by the shafts 96 and 98. The mechanism for moving the mounting frame of the crystal will next be described.

Referring now again to the pointer 52 which engages within the bezel 48, this member is mounted on a swivel 53 as shown, which is carried by a slider member 56 which is slideable toward and away from the grinding wheel in a channeled base or frame 54. The slider member 56 has a vertical upright 53 and the slider is normally urged away from the grinding wheel, by a tension spring 58, as shown. Thus it can be seen that the mounting of the pointer or follower 52 is such that it can accurately follow the contour of any bezel no matter what its shape, whether curved or otherwise.

The mechanism providing for transverse movement of the mounting frame for the crystal comprises a transverse channel member 62, as shown mounted on the base 10. Slidable within this channel member 62 is a slider 64 which can slide transversely, as shown. The slider 64 is pivoted by pin 106 to an arm as shown on the end of which is a circular member 22 which engages around an eccentric 20 on the shaft 28. Thus it can be seen that as the shaft 28 rotates, the action of the eccentric 20 within the ring 22 is to cause the slide 64 to slide back and forth in the slider base member 62.

Upstanding from the slider 64 are upright members 102 and 104 and engaged between these members on shaft 66 is cylindrical member 70 and from this member extends upwardly a shaft 72. The shaft 72 is rotatable in the cylindrical member 70 in the manner of a swivel for a purpose which will presently be made clear. On the end of the shaft or stem 72 is a U-shaped frame 73, as shown, which inclines towards the grinding wheel 14 in the position shown in Fig. 1. Spaced inwardly from the outer ends of the legs of the U-shaped member 73 and journaled for rotation therein is a shaft 74 and fixedly secured to the outer ends of the said shaft 74 are gears 76 and 80. Adjacent the ends of the legs of the U-shaped member 73 are a pair of axially aligned holes and in these holes are journaled for rotation the separate axially aligned shafts 114 and 116. A gear 82 is fixed to the shaft 114 immediately adjacent the outer face of a leg of the member 33 and meshes with the gear 80 and a bevel gear 88 is fixed to the end of said shaft 114 to mesh with the drive gear 90 previously described. A gear 78 associated with the shaft 116 meshes with the gear 76. The shafts 114 and 116 cooperate to drive the watch crystal as will be presently described in greater detail. The gears 80 and 82 and 76 and 78 are sized so that the shafts 114 and 116 will be positively driven at exactly the same speed. On the end of the shaft 116 is a knurled knob 86 for manually producing the clamping and unclamping operation of the crystal as will be described presently. From the foregoing, it can be seen that through the shaft 28 and the eccentric 20 the frame which mounts the crystal is moved transversely as respects the grinding wheel 14 and this is a uniform back and forth motion as can be seen, to prevent a groove being worn in the grinding wheel 14 by the crystal.

The details of the manner of clamping the

crystal to be ground between the arbors will be described presently in connection with Fig. 2.

The mechanism as previously described for producing motion of the crystal in conformity with the bezel includes in addition to the upright 53 extending upwardly from the slider 56, an arm 60 attached by slot 61 and a pin, as shown, to the upper end of upright 58 and the opposite end of this arm engaging the shaft or spindle 114. As may be seen in Fig. 7, coil spring 63 attached to arm 60 and upright 58 normally urges arm 60 in a direction to bring the pin in upright 58 toward the end of slot 61. Thus from the foregoing it can be seen that as the pointer or follower 52 follows the interior contour of bezel 48, the slider 56 is similarly moved through the arm 60, the frame on which the crystal 84 is mounted is moved toward and away from the grinding wheel in exactly the same manner. At the same time, the crystal is being rotated at exactly the same speed as the bezel 48. As previously pointed out, these various movements of the crystal are permitted by the universal joints and coupling in the drive to the crystal. The non-rigid attachment of arm 60 to upright 58 provides self-adjustment of the parts to accommodate crystals or blanks larger than the bezel to which they are to be ground to fit.

Referring now to Fig. 2 of the drawings, the mounting of the frame which holds the crystal is shown in detail in this figure. As may be seen in the figure, the slider 64 is shown, which slides in the block 62 mounted on base 10 as previously described. The stem 72 which carries the frame which mounts the crystal, as shown, extends into the cylindrical member 70 and is firmly held there by the set screw 68. The cylindrical member 70 is pivotally mounted on a shaft or spindle 66, the ends of which engage in bearings in the uprights 102 and 104 as shown. Thus as can be seen from Fig. 2 the frame can be pivoted about the shaft or spindle 66 in a direction into or away from the grinding wheel, the spindle 66 being held in place by set screw 138.

Similarly, by loosening the set screw 68 the frame mounting the crystal can be rotated about the axis of stem 72 for the purpose of grinding a bevel on the edge of the crystal, as will be referred to again presently. As may be seen in Fig. 2 the gears 80 and 76 on the ends of shaft 74 mesh with the gears 82 and 78 in the manner previously described. As shown in Fig. 2 on the ends of the arbors 114 and 116 are resilient cushions or pads 120 and 122 between which the crystal 84 is firmly engaged. As has already been pointed out the two arbors are separate, but synchronized and driven at exactly the same speed. Surrounding the arbor 116 and journaled for rotation in the leg of the U-shaped member 73 is a sleeve 118, said sleeve having the gear 78 fixedly attached thereto and being driven thereby. A pin 119 passes loosely through an elongated slot 118a in said sleeve and is fixedly secured in the spindle 116. Fixedly attached to the sleeve 118 is a transverse member 121, as shown, having inwardly extending arms 121a and 121b which are parallel to the sleeve 118. Pivotally attached to these arms 121a and 121b are the jaws 110 and 112, respectively. Between the transverse member 121 and the pin 119 is placed a stiff coil spring 123. This spring normally urges the pin 119 inwardly and consequently the shaft 116 will be braced inwardly and the jaw 122 will maintain a pressure against the crystal and the fixed jaw 120. The pin 119 serves to transmit the sleeve torque to the

arbor 116. The jaw members 110 and 112 are normally urged toward the transverse member by coil springs 124 and 126, as shown. The inner ends of the jaw members are adjacent the sleeve 118 and are engageable with the transverse pin 119 extending through sleeve 118, when the pin 119 is drawn outwardly by drawing outwardly on the arbor 116 and knurled knob 96. When the transverse pin 119 engages the inner ends of jaws 110 and 112 they are rotated about their pivots stretching springs 124 and 126 and the ends of the jaws then engage the edges of the crystal firmly and clamp it. In this operation the coil springs, as can readily be seen, pass over dead center and after passing over dead center hold the jaws firmly against the edges of the crystal 84, thus centering the crystal in and between the clamping jaws 120 and 122.

Referring now more particularly to Figs. 5 and 6 of the drawings the improved rotating chuck 42 is shown in detail. The chuck comprises a cylindrical member as shown which is driven by the shaft 34. Each of the individual jaw members operates in a transverse groove as shown in 20 the outer face of the cylindrical member, as shown. At the inner end of each of the jaw members as shown at 44b, 45b, 46b and 47b is a rectangular block which travels in a transverse 25 groove within the chuck 42. The individual jaws 30 of the two pairs of jaws, are spaced 90 degrees apart as may be seen in Fig. 6 and the transverse grooves in which the individual block members slide are spaced 90 degrees as shown in the figure. Each of the blocks has a screw-threaded bore and 35 passing through the bores are screw-threaded stems 49 and 51 as shown, and at the outer ends of the stems are knurled, rotating knobs 46 and 47 for one pair of jaws and 44 and 45 for the other pair of jaws. Each of the screw-threaded 40 stems extends through the blocks at the ends of one pair of jaws and each of the stems has right-handed threads on one side and left-handed threads on the other. Thus, it can be seen, that by rotating one of the knobs at either end of one 45 of the screw-threaded stems, its respective pair of jaws may be caused to close together or move apart. In this manner the two pairs of jaws can 50 be made to firmly and accurately engage within a rectangular bezel as shown at 46 in Fig. 1, no matter what the shape of the bezel is. As previously pointed out, the outer surfaces of the jaws may preferably be serrated or knurled in order to prevent slipping in their engagement with the interior of the bezel.

55 The foregoing is representative of preferred forms of our invention. Those skilled in the art will observe that we have provided a very effective and fully automatic device for grinding watch crystals or other crystals to any desired shape, and to a shape exactly in conformity with the bezel to which the crystal is to be fitted. It is to be observed that all of the motions and adjustments of the mechanism are positive in action and that once a crystal has been set on the machine for grinding to the desired size, the machine is fully automatic to grind it to the exact size to fit the bezel without attention from an operator. The machine may be set in motion and automatically stopped by a timer, if desired. 60 The mechanism provides convenient mechanical arrangements whereby the frame for mounting the crystal is readily adjustable away from the grinding wheel adapting it for grinding any size crystal or blank, even though it is larger 65 than the bezel to be fitted, and it will automatically 70 stop when the crystal is ground to the exact size. 75

cally adapt itself, once it has been set, to any size crystal.

By loosening set screw 68 stem 72 may be angularly rotated in hub 70, thus tilting frame 73 so that the crystal is positional at an angle to the grinding wheel for grinding a bevel at any desired angle on the crystal.

The arrangement which we have provided for mounting and rotating the bezel is very effective and convenient in that the two pairs of jaws are conveniently adjustable manually, and hold and retain the bezel in a manner such that it cannot get out of adjustment.

The foregoing is representative of a preferred form of our invention and such variations, modifications and alterations as may be made by those skilled in the art are intended to come within the spirit and scope of the claims appended hereto.

We claim:

1. In a watch crystal grinding machine, a base, a motor having a shaft extending transversely of the base, a grinding wheel fixed on said shaft, a worm fixed on said shaft, a second shaft extending longitudinally of the base, a worm wheel fixed on one end of the second shaft and meshing with said worm, a third shaft supported transversely of the base, bevel gears connecting the last mentioned shaft and the second shaft, a rocking frame supported from said base adjacent the grinding wheel, crystal holding means carried by the free end of said frame and including alined spindles, a telescopic shaft extending longitudinally of the base, a pair of bevel gears connecting the last mentioned transverse shaft and the telescopic shaft, said gears having a drive speed ratio of one to one, a pair of bevel gears connecting one of the spindles and the telescopic shaft, said last mentioned gears also having a drive speed ratio of one to one, a chuck for engaging a watch bezel fixed on the third shaft, a slide mounted on said base for movement longitudinally thereof, a feeler fixed on the slide for engaging a bezel held in the chuck, an arm projecting upwardly from said slide, and a link connecting the free end of said frame with said arm.

2. In a watch crystal grinding machine, a base, a motor having a shaft extending transversely of the base, a grinding wheel fixed on said shaft, a worm fixed on said shaft, a second shaft extending longitudinally of the base, a worm wheel fixed on one end of the second shaft and meshing with said worm, a third shaft supported transversely of the base, bevel gears connecting the last mentioned shaft and the second shaft, a rocking frame supported from said base adjacent the grinding wheel, the support for said frame including a slide movable transversely of the base, an eccentric disk fixed on the second shaft, an eccentric strap surrounding said disk and having an arm attached to said slide, crystal holding means carried by the free end of said frame and including alined spindles, a telescopic shaft extending longitudinally of the base, a pair of bevel gears connecting the last mentioned transverse shaft and the telescopic shaft, said gears having a drive speed ratio of one to one, a pair of bevel gears connecting one of the spindles and the telescopic shaft, said last mentioned gears also having a drive speed ratio of one to one, means to rock said frame, a chuck for engaging a watch bezel fixed on the third shaft, a slide mounted on said base for movement longitudinally thereof, a feeler fixed on the slide for engaging a bezel held in the chuck, an

arm projecting upwardly from said slide, and a link connecting the free end of said frame with said arm.

3. In a watch crystal grinding machine, a base, a motor having a shaft extending transversely of the base, a grinding wheel fixed on said shaft, a worm fixed on said shaft, a second shaft extending longitudinally of the base, a worm wheel fixed on one end of the second shaft and meshing with said worm, a third shaft supported transversely of the base, bevel gears connecting the last mentioned shaft and the second shaft, a rocking frame supported from said base adjacent the grinding wheel, crystal holding means carried by the free end of said frame and including alined spindles, a telescopic shaft extending longitudinally of the base, a pair of bevel gears connecting the last mentioned transverse shaft and the telescopic shaft, said gears having a drive speed ratio of one to one, a pair of bevel gears connecting one of the spindles and the telescopic shaft, said last mentioned gears also having a drive speed ratio of one to one, means to rock said frame, and means on one of said spindles for gripping opposite edge portions of a crystal to center said crystal.

4. In a watch crystal grinding machine, a base, a motor having a shaft extending transversely of the base, a grinding wheel fixed on said shaft, a worm fixed on said shaft, a second shaft extending longitudinally of the base, a worm wheel fixed on one end of the second shaft and meshing with said worm, a third shaft supported transversely of the base, bevel gears connecting the last mentioned shaft and the second shaft, a rocking frame supported from said base adjacent the grinding wheel, crystal holding means carried by the free end of said frame and including alined spindles, a telescopic shaft extending longitudinally of the base, a pair of bevel gears connecting the last mentioned transverse shaft and the telescopic shaft, said gears having a drive speed ratio of one to one, a pair of bevel gears connecting one of the spindles and the telescopic shaft, said last mentioned gears also having a drive speed ratio of one to one, a chuck for engaging a watch bezel fixed on the third shaft, a slide mounted on said base for movement longitudinally thereof, a feeler fixed on the slide for engaging a bezel held in the chuck, an arm projecting upwardly from said slide, a link connecting the free end of said frame with said arm, and means on one of said spindles for gripping opposite edge portions of a crystal to center said crystal.

5. In a watch crystal grinding machine, a base, a motor having a shaft extending transversely of the base, a grinding wheel fixed on said shaft, a worm fixed on said shaft, a second shaft extending longitudinally of the base, a worm wheel fixed on one end of the second shaft and meshing with said worm, a third shaft supported transversely of the base, bevel gears connecting the last mentioned shaft and the second shaft, a rocking frame supported from said base adjacent the grinding wheel, the support for said frame including a slide movable transversely of the base, an eccentric disk fixed on the second shaft, an eccentric strap surrounding said disk and having an arm attached to said slide, crystal holding means carried by the free end of said frame and including alined spindles, a telescopic shaft extending longitudinally of the base, a pair of bevel gears connecting the last mentioned transverse shaft and the telescopic shaft, said gears having a drive speed ratio of one to one, means to rock said frame, a chuck for engaging a watch bezel fixed on the third shaft, a slide mounted on said base for movement longitudinally thereof, a feeler fixed on the slide for engaging a bezel held in the chuck, an

shaft, said gears having a drive speed ratio of one to one, a pair of bevel gears connecting one of the spindles and the telescopic shaft, said last mentioned gears also having a drive speed ratio of one to one, means to rock said frame, a chuck for engaging a watch bezel fixed on the third shaft, a slide mounted on said base for movement longitudinally thereof, a feeler fixed on the slide for engaging a bezel held in the chuck, an arm projecting upwardly from said slide, a link connecting the free end of said frame with said arm, and means on one of said spindles for gripping opposite edge portions of a crystal to center said crystal.
